UNITED STATES PATENT OFFICE.

ARTHUR G. HAINLINE, OF LA ROSE, ILLINOIS.

LOADING CHUTE.

Application filed September 18, 1925. Serial No. 57,192.

This invention relates to new and useful improvements in loading devices and particularly to chutes for loading hogs into wagons.

One object of the invention is to provide a device of this character which is simple in construction, and which can be easily handled.

Another object is to provide a loading chute of this character which is easily and quickly separable so that the device may be conveniently stored when not in use.

Other objects and advantages will be apparent from the following description when taken in connection with the accompanying drawing.

In the drawing:

Figure 1 is a side elevation of a loading chute made in accordance with the present invention, and in set up position.

Figure 2 is a top plan view of the same.

Figure 3 is an enlarged fragmentary transverse sectional view on the line 3—3 of Fig. 2, showing the manner of connecting the sides of the chute to the bottom thereof.

Referring particularly to the accompanying drawing, 10 and 11 represent the sides of the chute. Each of the sides includes the vertical end posts 13 and 14, the former of which is considerably longer than the latter, as clearly seen in Figure 1. Connected to the upper and lower portions of the inner faces of the posts 13 and 14, and extending in parallel relation therebetween, are the side rails 15, it being noted that the lower rail 15 is connected to the post 14 adjacent the lower end while the other end of the rail is connected at some distance from the lower end of the post 13, whereby said rails incline downwardly toward the post 14. Connected to the mutually adjacent faces of the posts 13 and 14, of a side of the chute, in parallel relation to, and below the lower rail 15, is a floor supporting beam 12. Secured on the upper face of each of the lower rails

are the upwardly extending loops 16, to which reference will be made later herein.

There are two of these sides of the chute, as seen in Figure 2, and each including the posts 13 and 14, the rails 15, the floor supporting beam 12 and the loops 16, said sides being disposed in vertical parallel relation.

A bottom member including the transverse boards 17 and longitudinal stringers 17', is disposed between these side members, and secured to each side of the said member are the outwardly extending horizontal straps 18, each being arranged to pass through a loop 16, and receive a key or pin 19 through an opening in the outer end thereof, such pin or key being disposed outwardly of the side of the chute whereby to maintain the sides and bottom in proper relation so that the chute may be readily placed against a wagon to permit easy passage of hogs into the wagon. When the chute is not to be used the keys or pins 19 are removed, thus permitting the easy and quick withdrawal of the sides from the bottom, and the convenient storage of the chute.

What is claimed is:

A loading chute comprising a pair of side members and a bottom member, each of the side members including a pair of posts of different length, rails and a floor supporting beam extending between the posts of each side member, transverse loop members mounted on each beam, laterally extending straps on the floor member removably disposed in the said loops, and removable pins disposed through the ends of the straps outwardly of the loops.

In testimony whereof, I affix my signature.

ARTHUR G HAINLINE.
